Attorney

UNITED STATES PATENT OFFICE.

ROY L. NAUGLE, OF BLACKSTONE, VIRGINIA.

STEAM-GENERATOR.

1,275,290.

Specification of Letters Patent. Patented Aug. 13, 1918.

Application filed December 24, 1917. Serial No. 208,672.

To all whom it may concern:

Be it known that I, ROY L. NAUGLE, a citizen of the United States, residing at Blackstone, in the county of Nottoway and State of Virginia, have invented certain new and useful Improvements in Steam-Generators, of which the following is a specification, reference being had to the accompanying drawings.

10 This invention relates to certain improvements in steam generators and it is an object of the invention to provide a novel and improved device of this general character wherein a liquid fuel is employed and 15 wherein the water to be converted is delivered into a chamber wherein the combustion of the fuel occurs.

It is also an object of the invention to provide a novel and improved steam generator wherein fuel, air and water are delivered within a chamber at substantially equal pressure and so fed to and mixed within the chamber to bring about combustion within the chamber and converting the water into 25 steam so that all of the heat given off by the fuel is utilized.

The invention consists in the details of construction and in the combination and arrangement of the several parts of my improved steam valve whereby certain important advantages are attained and the device rendered simpler, less expensive and otherwise more convenient and advantageous for use, as will be hereinafter more fully set 35 forth.

The novel features of my invention will hereinafter be definitely claimed.

In order that my invention may be the better understood, I will now proceed to describe the same with reference to the accompanying drawings, wherein is disclosed a diagrammatic view illustrating a steam generator constructed in accordance with an embodiment of my invention.

45 As disclosed in the accompanying drawings 1 denotes a tank of predetermined dimensions and which is adapted to contain a supply of water and a supply of air under pressure. P denotes an elongated pipe of predetermined dimensions and which leads to an engine or the like. In communication with the pipe P through the closed end 2 thereof is a conduit 3 leading from a source of fuel supply and which source is herein disclosed as a tank 4. The fuel within the tank 4 is preferably crude petroleum. In

communication with the conduit 3 in close proximity to the point of communication of said conduit with the pipe P is a second conduit 5 leading from the upper portion of the tank 1 and through which the air in said tank 1 is adapted to pass. In communication the lower portion or bottom of the tank 1 is a conduit 6 leading to and communicating with the pipe P at a predetermined point inwardly of the closed end 2 thereof. Interposed in the conduits 5 and 6 are the manually operated controlling valves 7 and 7', respectively. The conduit 3 has also interposed therein a controlling valve 8. Also in communication with the tank 1 through the bottom thereof and with the tank 4 through the bottom of said last named tank is the conduit 9 whereby the pressure within the tanks 1 and 4 is equalized so that the fuel within the tank 4 is automatically forced upwardly and through the conduit 3. Also interposed in the conduits 3, 5 and 6 are the regulating valves 10 arranged in close proximity one to the other and provided with stems 11 extending exteriorly of said conduits. Each of the valves 10 has coacting therewith a spring 14 which constantly urges said valve into closed position.

Pivots engaged as at a with the stem 11 of the valve coacting with the air conduit 5 are the rods 12 which have their opposite end portions engaged with the sliding fulcrums 21 mounted upon the supports or guides 22. Pivots engaged as at b with the outer end portion of each of the rods 12 and inwardly of the adjacent fulcrum 21 is a stem 11 of each of the two remaining valves. By this arrangement it will be perceived that as the valve 10 coacting with the conduit 5 moves into open position, the remaining two valves will also be caused to move into an open position through the mediums of the rods 12. By adjusting the fulcrums 21, the lift of the valves coacting with the conduits 3 and 6 may be increased or decreased in accordance with the requirements of practice.

At a point intermediate the closed end 2 and the point of communication therewith of the conduit 6, the pipe P has depending therefrom a draft vent 15 having interposed therein the controlling valve 16 and positioned directly beneath the vent 15 is a gasoline torch 17 of any desired type. Also in communication with the portion of the pipe P intermediate the closed end 2 thereof and the point of communication therewith of the

conduit 6, is a priming cock 18 for a purpose which will hereinafter be more particularly referred to. At a predetermined location inwardly of the point of communication 5 of the conduit with the pipe P, said pipe P is provided with an up-standing vent 19 adapted for communication with the atmosphere and which has interposed therein the controlling valve 20.

- 10 In operation the delivery end of the pipe P is closed by a suitable valve (not shown) as is also the valves 7 and 8. The valves 16 and 20 are open. Before the valve 16 is opened, gasoline or other volatile liquid fuel 15 is delivered within the pipe P through the priming cock 18. After the valve 16 is opened, the torch 17 is lighted and the flame will pass through the draft vent 15 and ignite the fuel within the pipe and this flame 20 will discharge through the open vent 19. When sufficient heat has been generated 25 within the pipe P, the valve 7 is partially opened and the valve 8 completely opened. This will result in a mixture of air and fuel delivered in the pipe P through 30 the closed end thereof and which will be ignited within the pipe P. At this time the valve 16 is closed and the valve 7' opened to permit delivery of water into 35 the pipe P and the water as delivered within the pipe P will be converted into steam. When sufficient steam pressure has been generated 40 within the pipe P, the valve interposed therein at the delivery end is open as is also the valve 20, while the valves 7 and 7' are both opened wide. At this time the valves 10 automatically operate to control 45 the flow of fuel, air and water to the pipe P. It is to be noted that all three of the valves 10 are operated under control of the air pressure so that when the steam pressure within the pipe P is reduced, the pressure of the air will serve to cause the valves 10 to open and vice versa.
- 45 From the foregoing description, it is thought to be obvious that a steam generator constructed in accordance with my invention is particularly well adapted for use by reason of the convenience and facility with 50 which it may be assembled and operated and it will also be obvious that my invention is susceptible of some change and modification without departing from the principles and spirit thereof and for this reason I do not 55 wish to be understood as limiting myself to the precise arrangement and formation of the several parts herein shown in carrying out my invention in practice except as hereinafter claimed.

60 I claim:

1. A steam generator comprising a tank adapted to contain a supply of water and air under pressure, a fuel tank, a conduit affording communication between both of 65 the tanks through the lower portions there-

of, a steam pipe having an end closed, a conduit leading from the upper portion of the fuel tank and in communication with the pipe at the closed end thereof, a conduit leading from the upper portion of the 70 first named tank and communicating with the first named conduit at a point in close proximity to the pipe, a conduit leading from the lower portion of the first named tank and in communication with the pipe 75 at a predetermined point inwardly of the closed end thereof, controlling valves interposed within each of said conduits and provided with means for constantly urging said valves toward their seats, and means for 80 causing said valves to move in unison and in the same general direction.

2. A steam generator comprising a tank adapted to contain a supply of water and air under pressure, a fuel tank, a conduit 85 affording communication between both of the tanks through the lower portions thereof, a steam pipe having an end closed, a conduit leading from the upper portion of the fuel tank and in communication with the pipe at the closed end thereof, a conduit leading 90 from the upper portion of the first named tank and communicating with the first named conduit at a point in close proximity to the pipe, a conduit leading 95 from the lower portion of the first named tank and in communication with the pipe at a predetermined point inwardly of the closed end thereof, controlling valves interposed within each of said conduits and provided with means for constantly urging said valves toward their seats, means for causing 100 said valves to move in unison and in the same general direction, and a valve controlled vent in communication with the pipe 105 and with the atmosphere.

3. A steam generator comprising a tank adapted to contain a supply of water and air under pressure, a fuel tank, a conduit affording communication between both of 110 the tanks through the lower portions thereof, a steam pipe having an end closed, a conduit leading from the upper portion of the fuel tank and in communication with the pipe at the closed end thereof, a conduit leading from the upper portion of the 115 first named tank and communicating with the first named conduit at a point in close proximity to the pipe, a conduit leading from the lower portion of the first named tank and in communication with the pipe 120 at a predetermined point inwardly of the closed end thereof, controlling valves interposed within each of said conduits and provided with means for constantly urging said valves toward their seats, means for causing 125 said valves to move in unison and in the same general direction, a valve controlled vent in communication with the pipe and with the atmosphere, and a valve controlled 130

draft vent in communication with the pipe in close proximity to the closed end thereof.

4. A steam generator comprising a tank adapted to contain a supply of water and air under pressure, a fuel tank, a conduit affording communication between both of the tanks through the lower portion thereof, a steam pipe having an end closed, a conduit leading from the upper portion of the fuel tank and in communication with the pipe at the closed end thereof, a conduit leading from the upper portion of the first named tank and communicating with the first named conduit at a point in close proximity to the pipe, a conduit leading from the lower portion of the first named tank and in communication with the pipe at a predetermined point inwardly of the closed end thereof, controlling valves interposed

within each of said conduits and provided with means for constantly urging said valves toward their seats, means for causing said valves to move in unison and in the same general direction, a valve controlled vent in communication with the pipe and with the atmosphere, a valve controlled draft vent in communication with the pipe in close proximity to the closed end thereof, and a torch positioned adjacent the outer end of the draft vent.

In testimony whereof I hereunto affix my signature in the presence of three witnesses.

ROY L. NAUGLE.
